UNITED STATES PATENT OFFICE.

JOHANN G. PETERSON, OF HARTFORD, CONNECTICUT.

ELECTRIC SWITCH.

1,043,718.

Specification of Letters Patent.

Patented Nov. 5, 1912.

Application filed April 22, 1912. Serial No. 692,482.

To all whom it may concern:

Be it known that I, JOHANN G. PETERSON, a citizen of the United States, residing at Hartford, in the county of Hartford and 5 State of Connecticut, have invented certain new and useful Improvements in Electric Switches, of which the following is a specification.

This invention relates to electric switches, 10 the object of the invention being to provide a simple and effective article of this character which can be inexpensively made, and the parts of which can be readily and easily assembled and which also has means for insuring accurate action of the moving parts.

The switch possesses many other features 15 of advantage and novelty which with the foregoing will be set forth at length in the following description wherein I will outline 20 in detail that form of embodiment of the invention which I have selected for illustration, in the drawings accompanying and forming part of the present specification, this showing being primarily provided to 25 enable those skilled in the art to practice the invention, from which it will be evident that I do not limit myself to said disclosure; I may depart therefrom in several respects 30 within the scope of the invention included in the claims following said description.

Referring to said drawings: Figure 1 is 35 a top plan view of a switch involving my invention with a portion thereof broken away to better show certain of the parts. Fig. 2 is a vertical sectional view of said 40 switch. Fig. 3 is a transverse section on the line 3—3 of Fig. 2 looking in the direction of the arrow. Fig. 4 is a perspective view of an insulating member, and, Fig. 5 is a detail view of a key.

Like characters refer to like parts throughout the several figures.

The supporting body for the switch may 45 be of any desirable construction, although it is represented as consisting of a block of insulating material as 10 made from any of the suitable substances or compositions now commonly employed for this purpose. A switch of the type shown comprises a 50 switch member or blade carrier as 11 and a rocker as 12, both these parts being sustained by a spindle as 13 which in the construction shown is supported by a bracket as 14 situated in the chamber or hollow of the 55 block 10 and fastened therein in some suitable manner for instance by the screws 15

extending through the bottom or inner portion of the block or supporting body 10 and tapped into the elongated base portion of the bracket 14, the side branches of which directly support the spindle 13 to which reference has been made. The switch member or blade carrier 11 and the rocker 12 which coacts therewith are common in this art, and therefore it is needless for me to 60 describe the same in detail, it being well understood that when the rocker 12 is shifted in one direction, the switch member 11 will be operated to open the circuit controlled by the switch, while when said rocker is moved in the opposite direction the 65 circuit will be closed, all as will be well understood, for which reason it is needless for me to describe the same. As a means for operating the rocker the levers 16 and 17 are shown, 70 the lever 16 being out while the lever 17 is in, both of them as will be clear having an operative connection with the rocker as for example by providing said levers 16 and 17 with offsets 18 slotted to receive lateral extensions of the rocker 19, this providing one 75 simple way of uniting the respective levers 16 and 17 with the rocker 12. The levers 16 and 17 are provided with heads 20 by which 80 said levers can be operated, and these heads or their equivalents may vary as to character 85 each of them, however, having a V-notch 21 to receive a key as will hereinafter appear, the side walls of the notches converging 90 downwardly to facilitate the operation of said levers by such a key.

The supporting member or bracket 14 in the construction shown bears a plate as 22, the side arms or branches of said brackets being cut away near their upper ends to 95 form the projections 23 which extend through parallel, elongated slots in the plate 22 near opposite sides thereof. Owing to the fact that the side arms of said bracket are thus cut away there are formed shoulders as 24 at opposite sides of the projections 23 upon which the plate 22 rests. The plate 22 is provided with pendent or inwardly extending flanges 25 preferably formed integral therewith and arranged in 100 pairs at its opposite sides and which are divided or slotted as at 26 to receive the laterally extending arms 27 on the bodies of the respective levers 16 and 17 so as to accurately 105 guide said levers as they move inwardly and outwardly, the terminals of said arms or lateral extensions 27 being bent upon them- 110

selves as at 28 to fit against the outer faces of the respective flanges or wings 25 to thereby limit or prevent side motion of the two levers. It should also be stated that the 5 plate 22 is perforated near its opposite ends as at 29 for the passage of the levers 16 or at least the head or upper portions of said levers, each lever when in its outward position extending outwardly beyond the plate 10 10 22 through a co-operating hole or perforation 29.

Fitted against the plate 22 is a body of insulation and which as shown consists of the sheet 30 having holes or perforations 31 15 near its opposite ends a trifle larger in diameter than the holes or perforations 29, although the axes of the respective holes are in coincidence. This insulating sheet 30 has at or near its side edges elongated slots as 32 to receive the reduced portions of the extensions 23 to which I have already referred, these extensions 23 serving to steady the plate 22 and the sheet of insulation, the width of which latter is approximately equal 25 to the width of the chamber of the supporting body 10. The insulating sheet 30 is shown provided at its corners with tongues 33 which are deflected downward and which practically close the openings in the block 30 10 through which the lead wires (not shown) extend to thereby aid in making the switch safe. The plate 22 supports the slotted members 34 and 35, said slotted members being shown as disks or buttons the inwardly extending annular flanges of which fit directly 35 against said plate and closely within the openings 31, said slotted members or disks 34 being held in place by an interlocked connection with the plate 24 for example by 40 providing said slotted members or disks with bent lugs as 36 of approximately L-shape and which closely fit the slots 26, this providing a simple means of preventing the buttons from turning. The slots in the but- 45 tons or disks 34 and 35 are shaped to receive a specific kind of key, and by passing such a key through either of the slots, the lever (either 16 or 17) which operates the switch can be operated, said lever being thrust in- 50 ward by a push on said key, such as that shown in Fig. 5 and designated by 37. Fitted against the insulating sheet 30 is a bar or plate 38, this bar or plate having openings between its ends to receive the two 55 buttons 34 and 35 and being also fastened

to the block 10 by screws as 39. The plate or bar 38 which is also known as a yoke near its opposite ends is fitted in channels or grooves 40 in the outer face of the block or supporting body 10. In mounting the 60 switch the block 10 is set in an opening or chamber formed in the part with which it is associated and the terminal portions of the plate 38 are countersunk usually in such supporting part of whatever character the 65 same may be and are fastened therein in some suitable manner by screws or otherwise.

What I claim is:

1. A switch comprising a rocker, a lever 70 for operating said rocker, and a plate having an opening through which said lever is adapted to extend, said plate having inwardly extending slotted flanges, the lever having arms extending through the slots of 75 said flanges, the outer ends of said arms being bent on themselves to engage the outer faces of said flanges.

2. A switch comprising a rocker, a lever for operating said rocker, and a pair of relatively fixed slotted members, said lever having laterally extending arms extending through the slots of said slotted members, the outer ends of said arms being bent to engage the outer surfaces of said slotted 85 members.

3. A switch comprising a supporting block, a rocker in the block, a plate also in the block, a lever for operating the rocker, the plate having an opening to receive the 90 lever, a sheet of insulating material fitted against the plate, a bar fitting against the insulating material and secured to the block.

4. A switch comprising a supporting block, a rocker in the block, a plate also in 95 the block, a lever for operating the rocker, the plate having an opening to receive the lever, a sheet of insulating material fitted against the plate, and a bar fitting against the insulating material and secured to the 100 block, the latter having channels for lead wires and the insulating material having tongues extending across the inner ends of the channels.

In testimony whereof I affix my signature 105 in presence of two witnesses.

JOHANN G. PETERSON.
